UNITED STATES PATENT OFFICE.

JAMES G. DICKSON, OF GLENCOE, ILLINOIS.

SPARK PLUG.

Application filed August 24, 1926. Serial No. 131,181.

This invention relates to that class of spark plugs in which an intermediate electrode is arranged between the sparking terminals of the appliance, an example of 5 which is shown in the prior Dickson Patent No. 1,414,806, of May 2, 1922. And the present improvement has for its object:—

To provide a structural formation and combination of parts and features in a spark 10 plug of the above mentioned class, wherein an intermediate electrode of a rod form is supported in a substantial manner against displacement in actual use, with such arrangement coacting with an open bottom 15 cylindric bore or chamber formed in the lower part of the plug housing by an annular depending skirt portion the bottom face of which portion is of a plane or flat form, in order to attain a maximum scouring 20 action upon the sparking terminals and intermediate electrode, keeping same from an accumulation of carbonaceous matter and the formation of a short circuit between the parts. Such scouring action being effected 25 by the expansion of the compressed gases in said bore or chamber of the plug housing, all as will hereinafter more fully appear.

In the accompanying drawing:

Fig. 1, is an elevation of a spark plug 30 having this invention applied, the lower portion of the enclosing shell being shown in section to disclose the internal arrangement of parts.

Fig. 2, is bottom view of the same.

Fig. 3, is a detail section on a plane at 35 right angles to the plane of Fig. 1.

Fig. 4, is a similar view of a modification.

Like reference numerals indicate like 40 parts in the different views.

The constructions shown of a spark plug, is of the generally used type in which an outer metallic shell is formed to screw into 45 an opening in the wall of an engine cylinder, with its upper portion 1 internally screw-threaded for the reception of a sleeve nut 2 by which the central core 3 of insulating material is held in place, with said core carrying one terminal point or stem 4, which in the present invention depends from the 50 center of the core 3 and is deflected laterally so that its lower portion will be in spaced relation to the hereinafter described intermediate electrode.

The other and companion terminal point 55 or stem 5, is fixed by its outer portion in the annular wall of the skirt portion 6 of

the enclosing shell 1, with the inner portion of said stem 5 projecting into the cavity of said skirt portion 6 and deflected downwardly to have spaced relation to the intermediate electrode above referred to, and opposed relation to the aforesaid point or stem 4.

As usual in the present type of spark 60 plugs, and more especially in the present co-acting combination and formation of parts, the aforesaid annular skirt portion 6 of the shell or housing 1 provides an open bottom compression chamber in said shell or housing, and a material part of the present combination of parts involves a plane or smooth 65 surface formation of the under surface and lower end of the annular skirt portion of the plug housing, and which provides the open bottom chamber of said housing with 70 a view to assist in the rapid expansion and easy out passage of the compressed gases after they have been fired. With such rapid movement of the exploded gases, the same 75 will act in an effective manner to dislodge any carbon and oil coatings upon the transversely arranged electrode, associated inwardly projecting insulating bushings and 80 respective supply and return terminals 85 which in the present construction are located in the lower portion of said open bottom chamber.

In the present improvement, the intermediate electrode 7 is formed by piece of 90 rod metal or similar conducting material, 90 extending transversely, and preferably diametrically of the cavity of the skirt portion 6 of the enclosing shell 1, and supported in place by socket plugs or bushings 8, of insulating material, fixed in the wall of said 95 skirt portion 6, and with the aligned socket cavities of the bushings receiving and supporting the respective ends of such rod electrode 7.

Usually cushions 9 of elastic fireproof material will be arranged in the bottom portions of such cavities to hold said rod electrode from shifting endwise and at the same time permit of differential expansion and contraction of the parts in actual use.

In the preferred construction shown in Figs. 1, 2 and 3, which is intended for engines of the medium compression type, the intermediate electrode 7 will be positioned in the skirt portion 6 immediately 100 above a pair of diametrically opposed semi-circular notches 10 formed in the wall of 105

such skirt portion. Such construction is intended to permit ready outward flow of the initial flame of an explosion in an approximately horizontal plane into the combustion chamber of the engine cylinder. Such provision may however be dispensed with in spark plugs intended of engines of the high compression type, and the intermediate electrode 7 nearer the lower end of the skirt portion, as shown in Fig. 4.

Having thus fully described my invention what I claim and desire to secure by Letters Patent, is:—

1. In a spark plug of the type described, the combination of an enclosing shell having an annular depending skirt portion providing an open bottom chamber at the lower end of the plug housing, the lower end of the skirt portion having a plane form, a supply terminal stem depending within said bore, a return terminal stem fixed at one end in the wall of said skirt portion, and an intermediate electrode of the rod form arranged transversely in the lower end of the bore of said skirt portion and in angular relation to and in line with the aforesaid return terminal stem, said intermediate electrode being supported at its respective ends

in an insulated manner in the annular wall of said skirt portion by individual insulating sockets fitted to orifices in the wall of the aforesaid skirt portion.

2. In a spark plug of the type described, the combination of an enclosing shell having an annular depending skirt portion providing an open bottom chamber at the lower end of the plug housing, the lower end of the skirt portion having a plane form, a supply terminal stem depending within said bore, a return terminal stem fixed at one end in the wall of said skirt portion, an intermediate electrode of the rod form arranged transversely in the lower end of the bore of said skirt portion and in angular relation to and in line with the aforesaid return terminal stem, and insulating sockets arranged in the wall of said skirt portion and projecting into the bore of the same to constitute supports for the respective ends of the intermediate electrode at points inwardly remote from the inner face of said skirt portion.

Signed at Chicago Illinois, this 20th day of August, 1926.

JAMES G. DICKSON.
